US0D1105668S

(12) **United States Design Patent** (10) **Patent No.:** **US D1,105,668 S**
(45) **Date of Patent:** **** Dec. 9, 2025**

(54) **VACUUM CLEANER**

(71) Applicant: **GUANGDONG DEERMA TECHNOLOGY CO., LTD.**, Foshan (CN)

(72) Inventors: **Wenwu Li**, Guangdong (CN); **Long Chen**, Guangdong (CN)

(**) Term: **15 Years**

(21) Appl. No.: **35/521,704**

(22) Filed: **Jun. 28, 2024**

(80) **Hague Agreement Data**

Int. Filing Date: **Jun. 28, 2024**

Int. Reg. No.: **DM/238356**

Int. Reg. Date: **Jun. 28, 2024**

Int. Reg. Pub. Date: **Jul. 19, 2024**

(30) **Foreign Application Priority Data**

Dec. 28, 2023 (CN) 202330864616.3

(51) **LOC (15) Cl.** **15-05**

(52) **U.S. Cl.**

USPC **D32/22**

Assistant Examiner — Taylor O Mortorff

(57) **CLAIM**

The ornamental design for a vacuum cleaner as shown and described.

DESCRIPTION

1. Vacuum cleaner

1.1 : Perspective

1.2 : Perspective

1.3 : Front

1.4 : Back

1.5 : Left

1.6 : Right

1.7 : Top

1.8 : Bottom

FIG. 1.1 to FIG. 1.8 show a vacuum cleaner according to the present design. The broken lines illustrate portions of the vacuum cleaner that form no part of the claimed design.

1 Claim, 8 Drawing Sheets
